Primary Examiner — Melanie H Tung*Assistant Examiner* — Fitzgerald L Butac(74) *Attorney, Agent, or Firm* — Rankin, Hill & Clark LLP(57) **CLAIM**

The ornamental design for a pressure sensitive sensor, as shown and described.

DESCRIPTION

FIG. 1 is a perspective view of a pressure sensitive sensor; FIG. 2 is a front side elevation view thereof; FIG. 3 is a rear side elevation view thereof; FIG. 4 is a right side elevation view thereof; FIG. 5 is a left side elevation view thereof; FIG. 6 is a top plan view thereof; and, FIG. 7 is a bottom view thereof.

The broken lines in the drawings depict portions of the pressure sensitive sensor that form no part of the claimed design.
